Primary Examiner — Catherine R Oliver-Garcia

(74) Attorney, Agent, or Firm — Tuggle Duggins P.A.;
Blake P. Hurt(57) CLAIM

The ornamental design for a shopping bag canister, as shown and described.

DESCRIPTION

FIG. 1 is a top, front, right side perspective view of a shopping bag canister showing our new design;
 FIG. 2 is a bottom, rear, left side perspective view thereof;
 FIG. 3 is a front elevational view thereof;
 FIG. 4 is a rear elevational view thereof;
 FIG. 5 is a top plan view thereof;
 FIG. 6 is a bottom plan view thereof;
 FIG. 7 is a left side elevational view thereof;
 FIG. 8 is a right side elevational view thereof; and,
 FIG. 9 is a cross-sectional view as taken along lines 3-3 of FIG. 3.

The broken lines illustrate portions of the shopping bag canister that form no part of the claimed design.

1 Claim, 9 Drawing Sheets
